UNITED STATES PATENT OFFICE

JACOB VAN DEN BERGH, OF NIJMEGEN, NETHERLANDS, ASSIGNOR TO NAAMLOZE VENNOOTSCHAP GEBRS. VAN DEN BERGH'S INDUSTRIE EN HANDELMAATSCHAPPIJ, OF NORTH BRABANT, NETHERLANDS, A COMPANY OF THE NETHERLANDS

PROCESS FOR THE MANUFACTURE OF CURTAIN AND SIMILAR WOVEN STUFF

Application filed May 29, 1929, Serial No. 366,989, and in Germany March 27, 1929.

- The invention has for its object the manufacture of curtain- and similar woven stuff, which is useful on both sides and therefore, hitherto had to be provided with a lining.
- 5 The process according to the invention enables one to manufacture a texture, which on both sides possesses the desired condition, colour or pattern, so that the application of a lining can be saved.
- 10 The process consists in adding to the usual warps for the manufacture of the singular texture an auxiliary or third warp, which is a design warp forming with the weft threads a texture turned towards the reverse side and
- 15 entirely apart from the texture on the face side, the ground-warp serving for both textures simultaneously.

In the accompanying drawing, Fig. 1 represents diagrammatically material forming the 20 subject-matter of the present invention as produced in a single loom; and Fig. 2 a similar view of material produced in a double loom.

A simple form for the binding of such a 25 tissue is illustrated in Figure 1, whereby on one side a plush and on the other side a smooth figured design is formed.

The pile-warp p forms with the weft threads 3, 5, 7 etc. and the groundwarp- 30 threads 1 and 2 the plush for one side, whereas the weft threads 4, 6, 8 etc. form with the third warp f (the figure-warp) the figured side, so that on the tensioned warp 1 and binding warp 2 on both sides a texture of the 35 desired condition, colour and pattern is formed.

The third warp f may be also a pile-warp, so that on both sides plush is obtained or inversely the pile-warp p may be a figure- 40 warp, so that both sides are figured with the same or with a different pattern. All combinations, which in the art of weaving by means of the choice of the materials, colours and patterns can be obtained, may be applied 45 in this tissue on both sides.

It is not necessary to use the weft threads alternately for one texture and for the other, as is supposed in Figure 1. This method, however, is to be preferred, as in this manner the ground warp separates the two textures 50 completely from each other and hence on one side nothing can be seen of the texture on the other side.

The application of other, eventually more complicated bindings remains in the process 55 according to the invention completely free, whereas, as is illustrated in Figure 2, the invention can also be applied in a double loom.

For the same example, according to Figure 2, f_1 and f_2 are the two figure-warps (third warps), g_1 and g_2 the ground-warp for one 60 texture and g_3 and g_4 the ground-warp for the other texture. The pile-warp p , which with the weft threads has to form the plush- 65 texture for both textures, is cut through along the line m by the knife.

In manufacturing jacquard textures the effect can be obtained on both sides in each 70 desired colour by means of the welt.

What I claim is:

1. A woven fabric for curtains or similar hangings comprising a woven web formed of a single series of tensioned warp threads extending substantially straight therethrough, 75 a single series of warp threads shedded alternately above and below said series of tensioned warp threads, weft threads inserted in the sheds formed by said two series of warp threads, design pile loops extending about all 80 the weft threads on the same side of the tensioned warp threads to form a patterned surface, and a second series of design pile loops extending about all the weft threads on the other side of the tensioned warp threads to 85 form a like or different patterned surface, the pile loops and their engaging weft threads being on the same side of the tensioned warp threads respectively, whereby the patterned surface on each face is distinct from that on 90

the other face and invisible from the other face.

2. A woven fabric as claimed in claim 1 wherein the fabric is woven as a double web having the webs in superposed relation and the pile forming threads extend from the weft threads on the inner side of the tensioned warp threads in one web to the next adjacent weft threads on the inner side of the tensioned warp threads on the second web, said pile forming threads adapted to be cut to form separate webs.

In testimony whereof I affix my signature.

JACOB VAN DEN BERGH.
